UNITED STATES PATENT OFFICE.

JACOB WISSLER, OF LYNDHURST, VIRGINIA.

LAND-ROLLER.

1,004,719.

Specification of Letters Patent.

Patented Oct. 3, 1911.

Application filed April 25, 1911. Serial No. 623,264.

To all whom it may concern:

Be it known that I, JACOB WISSLER, a citizen of the United States, residing at Lyndhurst, in the county of Augusta and State 5 of Virginia, have invented a new and useful Land-Roller, of which the following is a specification.

This invention relates to land rollers and its object is to provide a motor propelled device 10 of this type capable of use as a tractor for drawing harrows, drills, etc., and which utilizes two separate motors, said motors driving speed reducing mechanisms which, in turn, operate separate rollers and have 15 separate controlling means whereby the power applied to the drive rollers of the machine can be varied at will.

A further object is to provide a roller on which the frame of the machine is tiltably 20 mounted, the said rollers being separately movable laterally relative to the frame so as to conform to irregularities in the contour of the surface over which they are traveling.

Another object is to provide a steering 25 roller made up of sections, certain of the sections being loosely mounted on a shaft extending through all of them and whereby the said roller can be readily turned for the purpose of steering the machine.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed can be made within the scope of what is claimed without departing from the spirit of the invention.

In the accompanying drawings the preferred form of the invention has been shown.

In said drawings:—Figure 1 is a plan view of the machine. Fig. 2 is a side elevation thereof, a canopy being shown in 45 position upon the machine. Fig. 3 is an enlarged front elevation of one of the propelling rollers, a portion of said roller being broken away to show the shafts therein and one of the positions of the roller, when 50 passing over an irregular surface, being indicated by dotted lines. Fig. 4 is a view

partly in section and partly in elevation of the steering roller.

Referring to the figures by characters of reference, 1 designates a frame made up of 55 any preferred arrangement of longitudinal and cross beams and arranged at the center of this frame adjacent the front end thereof is an upstanding stem 2 having a yoke 3 at its lower end and within which a shaft 4 60 is journaled. This shaft extends through a series of roller sections 5, three of these sections being shown in the present instance. The middle one of the sections is keyed or otherwise secured to the shaft, as indicated 65 at 6 while the other sections are loose on the shaft. A steering lever 7 extends rearwardly from the upper end of the stem 2 and to a point where it can be conveniently reached by the operator occupying a seat 8 70 arranged at the back end of the frame 1.

Extending upwardly from the rear portion of the frame 1 and between the seat 8 and each side of the frame is a pair of standards 9 connected, adjacent their upper ends, 75 by a bearing pin 10 extending in the direction of the length of the machine. The standards 9 are mounted on transverse frame members 11 and 12 and each pair of standards is equidistant from two sets of hangers 80 13 secured to and extending downwardly from the beams 11 and 12. These hangers are arranged in pairs and constitute guides for trunnions 14 extending from the ends of rollers 15. These trunnions are preferably 85 formed by extending a shaft through a roller and having its ends project beyond the ends of said roller, as clearly indicated in Fig. 3, said shaft being keyed or otherwise secured to the roller, as shown at 16. 90 These trunnions are journaled within the ends of a yoke 17 which is slidably mounted between the frame members or beams 11 and 12 and extends upwardly to the adjacent bearing pin 10, the crown portion of the 95 yoke having an angular depression or seat 18 in which the bearing pin is mounted. It will thus be seen that the entire weight of the rear portion of the machine is applied to the yoke 17 by the pins 10 and is thus transmitted to the rollers 15. Said rollers, however, are free to shift laterally relative to

the frame by moving about the bearing pins 10 as centers, and as indicated by full and dotted lines in Fig. 3. Each shaft 14 has a sprocket 19 secured thereto, said sprocket receiving motion, through a chain 20, from a sprocket 21 secured to a drive shaft 22. This shaft is journaled upon the frame 1 and one of these shafts is provided for each roller 15, the two shafts being preferably disposed in alinement and being located adjacent opposite sides of the frame. A gear 23 is loosely mounted on each shaft 22 and a friction clutch 24 is preferably utilized for coupling this gear to the shaft, said clutch being operated by a lever 25 extending close to the seat 8. Each gear 23 meshes with another gear 26 connected to the shaft 27 of a motor 28, one motor being provided adjacent each shaft 22.

In using the machine the two clutches 24 are first disengaged from the gears 23 after which the motors 28 are started and gears 23 will therefore be rotated freely upon their shafts 22. By simultaneously shifting the levers 25, both clutches 24 can be brought into engagement with the gears 23 and power will therefore be transmitted from the motors to the rollers 15 and these rollers will propel the machine forwardly or rearwardly, according to the direction in which the shafts 22 are operated. During the travel of the machine the same can be readily steered by means of lever 7, the central roller section 5 being readily movable about the longitudinal axis of the stem 2 for the reason that the other roller sections are loosely mounted on the shaft 4 and can therefore rotate at different speeds and in opposite directions. All of said sections, however, operate efficiently to crush clods of earth in the path thereof, the path covered by this steering roller being equal to or slightly greater than the distance between the propelling rollers 15. These last mentioned rollers are free to tilt laterally as the machine moves over the ground, said rollers thus readily conforming to any irregularities in the contour of the surface of the ground. The chain drive utilized for transmitting motion to the rollers 15 is sufficiently flexible to permit this tilting movement of the rollers without causing displacement of the parts of the driving mechanism. Whenever deemed desirable the power applied to either one of the rollers 15 can be increased or diminished relative to that applied to the other roller, this being especially desirable for overcoming side draft and for facilitating the turning of the machine.

In order that the occupant or occupants of the machine may be protected from the direct rays of the sun and from rain, a canopy 29 is preferably erected upon the frame 1 and, as shown in Fig. 2, this canopy can

be extended over the entire frame so as to protect the mechanism thereon.

While the machine can be used as a land roller it is to be understood that it can also be employed for simultaneously rolling the ground and at the same time drawing harrows, drills or other agricultural machines thereafter. The machine can also be employed as a tractor for pulling plows.

What is claimed is:

1. A machine of the class described including separately movable rollers, trunnions extending therefrom, yokes supported by and upstanding from the trunnions, a frame, bearing elements extending longitudinally of the frame and removably seated upon the yokes and constituting pivots therefor, and a steering element supporting one end portion of the frame. 75

2. A machine of the class described including separately movable rollers having trunnions, yokes supported by said trunnions, a frame, means thereon for detachably engaging the yokes to support one end portion of the frame, said yokes being adapted to swing about said means in a vertical plane extending transversely of the frame, steering means supporting one end portion of the frame, and separate means upon the frame for driving the respective yoke supporting 95 rollers. 90

3. The combination with a frame and depending guide hangers, of rollers having trunnions mounted to slide and rotate between the hangers, yokes carried by said trunnions and extending into the frame, means upon the frame for detachably engaging the yokes to support one end portion of the frame, said yokes being adapted to swing about axes extending longitudinally 100 of the frame, steering means for supporting one end portion of the frame, and means upon the frame for actuating the rollers. 105

4. In a machine of the class described, a frame, guide hangers depending therefrom, 110 rollers having trunnions mounted to slide and rotate between the guide hangers, yokes supported by the trunnions and projecting into the frame, said frame having means for holding the yokes against swinging movement about axes extending transversely of the frame, longitudinally extending bearing elements carried by the frame and detachably seated upon the yokes to support one end of the frame, said yokes being adapted 115 to swing about said elements as pivots, a steering element supporting one end portion 120 of the frame, and means for propelling the yoke supporting rollers. 120

5. A machine of the class described including a frame, propelling rollers, a shaft extending through and secured to each roller, a yoke bearing at its ends upon the projecting end portions of the shafts, each yoke having a central depressed portion con- 125

130

stituting a seat, standards upon the frame, bearing elements secured to the standards and seated within said depressed portions, separate motors upon the frame, and flexible power transmitting mechanism for transmitting motion from the motors to the shafts of the respective rollers.

In testimony that I claim the foregoing as my own, I have hereto affixed my signature in the presence of two witnesses.

JACOB WISSLER.
